WELL-DRILLING BIT

Paul A. McMurdy and Oscar N. Donehoo,
Houston, Tex.

Application December 10, 1949, Serial No. 132,326

7 Claims. (Cl. 255—61)

1

This invention relates to well drilling bits and it has particular reference to bits having interchangeable and replaceable blades.

The principal object of the invention is to provide a bit for the drilling of test holes, core drilling and the drilling of oil, gas and other wells, the peculiar adaptability of the bit for diversified drilling being made possible through a provision for interchanging the blades in a head for the selection of a blade design best suited for the work it is to perform. This is accomplished without the necessity for changing the blade retaining head since the interrelated elements responsible for retaining the blades in operative relation to the head remain the same regardless of any variation in the specific design of blade employed.

Another object of the invention is to provide a drill head having a tapered and threaded pin for its attachment to a drill stem and further having circumferentially spaced, longitudinal grooves or cavities which extend preferably above the mid-section of the unthreaded portion of the drill head, each groove broadening at its upper terminus into a circular cavity which is adapted to receive a correspondingly shaped prominence on the shank of a bit which lies in the groove and is effective to prohibit downward displacement of the bit with respect to the head. Moreover, to prevent outward displacement of the bit shank from its groove, a retaining sleeve having a smooth bore embraces the drill head and bit shanks and bears at its lower end on lateral arms formed on the shanks, thus to reinforce the latter against lateral pressure exerted on the bit.

Other objects will appear as the description proceeds, taken in connection with the accompanying drawing, wherein:

Figure 1 is an exploded view of a well drill bit constructed according to the invention.

Figure 2 is an elevational view of the bit assembled, partly in vertical section.

Figure 3 is a top plan view of the bit, and

Figure 4 is a transverse sectional view taken on line 4—4 of Figure 2.

This application is a continuation in part of applicants' copending application, Serial Number 46,258, filed August 26, 1948, now abandoned.

Continuing with a more detailed description of the drawing, reference numeral 10 denotes generally the drill head having an axial bore 11 and a tapered and threaded pin 12 which is adapted to be screwed into the drill stem 13, a portion of which is shown in Figures 1 and 2. Spaced circumferentially of the head 10 is a

2

series of longitudinal grooves 14 in the walls thereof, whose sides are parallel and which extend preferably past the midsection of the head, terminating in circular cavities 15. The lower end of the head is chamfered at *a* to accommodate the confronting edges of the series of blades 16 in the manner to be presently explained.

It is to be understood that the invention is not concerned with the particular shape or formation of the blades 16 since these elements will be designed to suit the peculiar work they are expected to accomplish. However, the invention does pertain to the manner in which the blades are attached to or installed in the drill head.

15 Each blade 16 is formed with a substantially straight walled shank 17 whose width equals that of the groove 14 in which it is adapted to lie, as shown in Figures 2 and 4. At the end of the shank is formed a circular head or prominence 18 which is received by the correspondingly shaped cavity 15 at the end of each slot or groove 14.

In applicants' earlier application above identified, the drill head is shown to possess tapered 25 slots or grooves receiving blade shanks of like formation but it is found that the blades 16 may be as securely held in the head in the manner herein described and more easily installed and removed than when the blade shanks are retained in tapered grooves, which latter are more difficult and costly to form.

The head 18 of the shanks prevent longitudinal displacement of the blades with respect to the head. To preclude lateral displacement, a 35 sleeve 19, having a smooth bore is slid onto the drill head to frictionally embrace the same and the exterior surfaces of the blade shanks 17, binding the same in their respective grooves. An internal annular flange 20 is formed on the sleeve 40 19 at its top and bears against an annular shoulder 21 on the drill head at the base of the threaded pin 12.

Each of the shanks 14 has formed thereon oppositely disposed and laterally extending arms 45 or wings 22 which are curved to conform to the body of the drill head against the chamfered portion *a* thereof. When all of the blade shanks are in position in the grooves of the drill head and the sleeve 19 applied thereto, the lower end of 50 the sleeve will bear against the collective arms of the shanks which form a complete circle around the drill head. Since the lower end of the drill stem bears against the upper end of the sleeve 19, the latter will not be displaceable longitudinally 55 and will thus present a bearing for the arms 22

of the shanks at its lower end to reinforce the blades 16 against lateral drag in drilling.

Manifestly, the construction as shown and described is capable of some modifications and such modification as may be construed to fall within the scope and meaning of the appended claims is also considered to be within the spirit and intent of the invention.

What is claimed is:

1. In a drill bit, a head comprising a cylindrical body having a chamfered lower end, the side wall of said head having therein a threaded pin on its upper end and a series of longitudinal circumferentially spaced grooves, each of said grooves having parallel walls terminating in a circular cavity, a series of blades projecting below said head, each having a shank shaped to conform to and lying in a respective groove of said head and having a circular prominence on its end lying in the circular cavity of said groove, said shanks each having oppositely directed and curved wings disposed in the chamfer of said head and a sleeve having a smooth bore embracing said head and engaging said shanks and wings collectively to hold said blades against lateral displacement in relation to said head.

2. A drill bit including a circular head having a drill stem engaging pin on its upper end and provided with a chamfered lower end, the side walls of said head having therein a series of circumferentially spaced, straight walled grooves opening at its periphery and lower end, said grooves each terminating at its opposite end in a cavity of like depth but of greater width than the groove, a series of blades projecting below said head, a shank on each of said blades having surfaces shaped to conform to the walls of said grooves and adapted to be interchangeably received therein whereby the outer surface of said shank will lie flush with the periphery of said head, a head on each of said shanks conforming with and lying in the cavity of a groove to preclude downward displacement of the shank thereon, a curved arm formed on each side of each of said shanks, said curved arms collectively defining a ring lying in the chamfered lower end of said head, and a sleeve embracing said head and engaging the outer surfaces of said blade shanks and arms to hold the same against outward displacement in said head.

3. A drill bit comprising a circular head having a chamfered lower end and longitudinal grooves in its sidewall and spaced about its circumference open at the lower end thereof, said grooves each having a widened area at its upper end, a series of blades extending below the lower end of said head a shank integral with each blade whose walls conform to those of said grooves to be conformably received therein, a prominence on the end of each of said shanks conforming in shape to and received in the widened area of said groove, arms integral with each of said shanks disposed in the chamfer of said head and curved to conform to the curvature of the latter, and a sleeve embracing said head and engaging said shanks and arms to hold the shanks against endwise and lateral displacement with respect to said head.

4. A drill bit comprising a circular head having a chamfered lower end and provided with

circumferentially spaced grooves in its side wall each open at its lower end and terminating in a cavity whose diameter is greater than the width of the groove, a blade for each groove extending below the bottom of said head, a shank on said blade conformably receivable in a groove of said head, a prominence on the end of said shank receivable in the cavity of said groove effective to hold said shank against longitudinal displacement in said groove curved arms on said shanks lying in said chamfered lower end and a sleeve having a smooth bore embracing said head and engaging said shanks and said arms to prohibit lateral displacement of said blades with respect to said head.

5. A drill bit, a circular head having a chamfered lower end and longitudinal grooves in its side wall, each groove being open at the lower end of said head and terminating in a circular cavity of equal depth but of greater width than said groove, a series of blades projecting below said head, a shank integral with each blade whose walls conform to and lie flush against the walls of a groove of said head, a circular prominence on the end of said shank and lying in said cavity to hold the shank against longitudinal displacement in said groove, a wing on each side of each of said shanks and disposed in the chamfer of said head the outer surface of said shanks and wings being flush with the periphery of said head and a sleeve snugly embracing said head and engaging said shanks and wings collectively to hold said blades against displacement with respect to said head.

6. A drill bit having a circular head and a chamfered lower end and provided with circumferentially spaced, longitudinal grooves in its side wall, each terminating in a widened area at its upper end, a series of blades extending below said head having shanks disposed interchangeably in said grooves each having a head shaped to conform to a widened area and disposed therein to hold the shank against longitudinal displacement in the groove, a sleeve embracing said head and shanks to prohibit lateral displacement of said shanks with respect to said head and oppositely extending arcuate wings carried by each of said shanks disposed in the chamfer of said head and engageable by the lower end of said sleeve to reinforce said blades against lateral pressure in drilling.

7. The structure of claim 6, the blade reinforcing means consisting of lateral wings on each blade shank collectively forming a ring embracing the drill head adjacent its lower end.
